(57) **CLAIM**

The ornamental design for a stadium situated bottle holder, as shown and described.

DESCRIPTION

FIG. 1 is a perspective view of the present invention, showing but not claiming a bottle seated within the stadium; FIG. 2 is a front view of the present invention showing but not claiming a bottle seated within the stadium; FIG. 3 is also a top view of the present invention; FIG. 4 is a side view of the present invention; FIG. 5 is a bottom view of the present invention; FIG. 6 is a rear view of the present invention; and, FIG. 7 is an alternate side view of the present invention showing but not claiming a bottle seated within the stadium. The broken lines in the drawings showing certain details of the stadium are for illustrative purposes only and do not form part of the claimed design. Specifically, the features of the stadium, comprising the outer and inner stadium surfaces, the lights, the steps, the tiers and the features on the front, rear and side concourse partitions are shown in broken lines and do not form part of the claimed invention. Also, the bottle, which may sit in the circular holder portion, is shown in broken lines and does not form part of the claimed invention. To the extent that any of the unclaimed features form an outer boundary of the design (as is the case with the outer stadium surfaces), the broken lines identify that Applicant is not claiming that particular section of the outer boundary as part of the claimed design.
